UNITED STATES PATENT OFFICE

CHARLES N. SOWDEN, OF GUANTANAMO, CUBA.

ACTUATING MEANS FOR SWIVEL LAMP-HOLDERS.

1,091,976.

Specification of Letters Patent. Patented Mar. 31, 1914.

Application filed July 16, 1913. Serial No. 773,901.

To all whom it may concern:

Be it known that I, CHARLES N. SOWDEN, a subject of the King of Great Britain, and a resident of Guantanomo, Santiago de Cuba Province, Cuba, have invented new and Improved Actuating Means for Swivel Lamp-Holders, of which the following is a full, clear, and exact description.

The invention relates to lamp holders for automobiles, locomotives and other vehicles having means for automatically turning the holder in the direction in which the vehicle is turned, and manually controlled actuating means.

The present invention is applicable to automatically controlled actuating means, manually controlled actuating means, or both, and it has reference more particularly to lamp holders and their appurtenances of the character forming the subject of the application for United States Patent filed by me November 1, 1912, Serial No. 728976, in which pull cords are connected with movable parts of the vehicle, and additional pull cords are under the control of the operator. In the said arrangement the pull cord at one side of the vehicle will be slackened when the vehicle turns, and the present invention provides a novel automatic take-up for the slack.

The invention will be particularly explained in the specific description following.

Reference is to be had to the accompanying drawings forming a part of this specification, in which similar characters of reference indicate corresponding parts in all the views:

Figure 1 is a side elevation of a portion of an automobile showing a practical embodiment of my invention applied thereto. Fig. 2 is a plan view of the elements shown in Fig. 1; Fig. 3 is a detail vertical section on a larger scale of the slack take-up as applied to the right hand lamp holder, the section being taken on the line 3-3 of Fig. 5; Fig. 4 is a similar view including a portion of the chassis and an idler thereon, and illustrating the relative movable parts of the take-up device in different positions from those shown in Fig. 3; and Fig. 5 is a cross sectional view on the line 5-5 of Fig. 4.

As fully set forth in my filed application above referred to, a vertical fork or yoke 10 is adapted to receive a lamp A of any approved form, and at the base of the yoke a

peripheral groove 11 is formed, in which a rope, cord or other flexible element 12 is given a partial turn, one end of the cord being secured to the yoke, as at 12^a, the cord passing from the yoke to a vertical sheave 13^a or drum 13^b. Associated with the sheave 13^a is a larger sheave 13, having the same axis of rotation. A pull cord 15 is given a partial turn on the sheave 13, and secured at one end to the latter, as at 15^a, said cord passing from the sheave 13 over idlers 14, 16, on chassis 17, and extending thence transversely to the opposite side of the vehicle where it has suitable connection with the arm 18 of the steering knuckle 18^a, in the event the invention is applied to an automobile. The yoke 10 and the described appurtenances and actuating devices are duplicated on each side of the machine, and it will be understood that in practice, the arms 18 are connected in the usual manner for operation in unison. In the present instance I have shown a transverse stretch 15^a of each rope as secured to an arm 18 for the automatic turning of the lamp holder with the steering devices.

The manually controlled means illustrated for turning each lamp holder comprises in the present instance a rope or its equivalent 21, connected to a transverse stretch 15^a as 25 at 20. At the point indicated by the numeral 22 there extends a further stretch of rope 23, to the lower end of a hand pull 24, for exerting a rearward pull on said stretch 23 and hence on the rope 21, and through the stretch 15^a on the rope 15, to exert a rearward pull on the latter for turning the lamp holder and lamp. From the point 22 also, or from an adjacent point, there extends from each rope 21, a stretch 25 of rope 95 which is given a bend around an idler 26 suitably supported on the vehicle to a connection with a lever 27 or its equivalent, to be actuated by the pedal 28 so that the lamp holder may be thus turned either by the foot 100 of the operator, or by hand.

It will be obvious that when the vehicle turns to the right, the right hand lamp will be turned to the right, but the cords 15^a and 15 of the opposite lamp holder will become 105 slack, and to take up this slack automatically, a flat coil spring 30 is connected at one end with a lug 31 on the sheave 13^a, and at its opposite end is secured to the hub 13^b of the sheave 13. The sheave 13 is formed with 110

a lug 32; the said lugs are disposed within the sheave 13 and in the path of rotation of each other.

As fully set forth in my above mentioned 5 application the yoke 10 is spring-acted, a coil spring in the base serving to return the yoke to the normal position after a movement in either direction. The spring 30 is of less strength than the spring in the yoke 10, 10 so that said spring 30 will not overcome the action of the spring in the yoke and turn the latter; on the contrary, the action of the spring 30 is localized, and is effective only to cause a relative turning movement of the 15 sheaves 13, 13^a.

Normally the sheaves 13, 13^a will be maintained in the positions shown in Fig. 3, with the lugs 31, 32, in contact at their opposed ends; if now the vehicle turns so as to exert a pull on the rope 15 attached to the 20 sheave 13, the said sheave will be turned to the left in the direction of the lug 31 of the sheave 13^a, and will thus carry the said sheave around, the two sheaves thereby moving in 25 unison in response to a pull on the rope 15, and the turning of the sheave 13^a will exert a pull on the flexible element 12 and turn the yoke 10 and the lamp A. If, on the other hand, the rope 15^a becomes slack, the 30 spring 30 will expand and will turn the sheave 13 relatively to the sheave 13^a, the lug 32 moving from the position shown in Fig. 3 to that shown in Fig. 4, the yoke 10 in the meantime remaining stationary because 35 of the greater strength of the spring in the base thereof. Obviously the relative turning of the sheaves 13, 13^a, will take up the slack in the rope 15, by winding the latter on the sheave 13. When the vehicle again 40 takes a straight direction and the two wheels are parallel with the vehicle, a pull will be exerted on that rope 15 the slack of which had previously been taken up, and the sheaves 13, 13^a will be restored (by the lug 45 31) to the positions shown in Fig. 3.

Having thus described my invention, I claim as new, and desire to secure by Letters Patent:

1. The combination with a spring pressed

swivel lamp holder and a flexible actuating 50 element therefor, of a slack take-up, comprising relatively movable sheaves, and an interposed spring connected respectively with said sheaves, the sheaves being provided with co-acting engaging members, the 55 spring when under tension tending to give a relative movement to the sheaves, and separate the mentioned members thereon, the one sheave having connection with the mentioned flexible element, and there being a 60 flexible element connecting the other sheave with the lamp holder; the spring pressure exerted on the lamp holder being greater than the tension exerted on the sheaves by the spring thereof so that the latter spring 65 may give a relative movement to the sheaves without affecting the lamp holder.

2. The combination with spring pressed swivel lamp holders, of sheaves, flexible elements connecting the said sheaves with the 70 respective lamp holders, a second sheave associated with each of the first mentioned sheaves, coil springs interposed between the sheaves and tending when under tension to give a relative movement thereto, lugs on 75 the sheaves in the path of movement of each other, a flexible element connected with each of the second mentioned sheaves, and winding in the reverse direction from the first mentioned flexible elements, and means for 80 exerting a pull on either of the mentioned flexible elements of the second sheaves.

3. In a device of the character described, relatively movable sheaves each adapted to receive a flexible element, a coil spring between the sheaves and tending, when under tension, to give a relative movement to the sheaves, and members on the sheaves in the path of movement of each other, the spring 85 normally tending to so turn the sheaves as to 90 separate the said members.

In testimony whereof I have signed my name to this specification in the presence of two subscribing witnesses.

CHARLES N. SOWDEN.
